UNITED STATES PATENT OFFICE.

MARGARET M. J. ROONEY, OF NEW YORK, N. Y.

DESIGN FOR A CRUMB-TRAY.

No. 38,037.

Specification for Design.

Patented May 29, 1906.

Application filed April 5, 1906. Serial No. 310,179. Term of patent 14 years.

To all whom it may concern:

Be it known that I, MARGARET M. J. ROONEY, a citizen of the United States, residing in the city, county, and State of New York, have invented a new, original, and ornamental Design for a Crumb-Tray, of which the following is a specification, reference being had to the accompanying drawings, forming a part thereof.

The drawings show, in Figure 1, a plan of the tray, and in Fig. 2 a transverse mid-section of the same, to illustrate the modeling and contour.

I claim—

The ornamental design for a crumb-tray, as shown.

MARGARET M. J. ROONEY.
